HEATER CONTROL

Application filed June 15, 1929. Serial No. 371,075.

This invention relates to controls for heaters and more especially to a furnace or boiler control utilizing damper mechanism for regulating the combustion in the boiler or furnace.

One of the principal objects of the present invention is to provide a control of this character which exercises positive and effective control over the draft through the fire and in 10 the stack thereby providing for such combustion as may be needed to meet the requirements of the system with which the heater is associated.

Another object of the present invention is 15 to provide a device of this character which is of simple and durable construction, reliable and effective in operation and easy and comparatively inexpensive to manufacture.

In carrying out the present invention an 20 automatic check draft damper is built into the stack or chimney and is so constituted as to automatically open and close in response to the draft through the stack. Thus, if the draft through the stack exceeds a predetermined point it sucks the check draft damper open with the result that cold air feeds directly into the stack, cools off the gases and cuts down the draft thereby retarding combustion in the heater. The check draft damper

25 is preferably in the form of a freely pivoted balanced damper biased by an adjustable weight to closed position. In conjunction with the weight, an additional or auxiliary biasing means is employed and is under the control of a room thermostat so that when the room thermostat is calling for heat the auxiliary biasing means will cooperate with the check draft damper to apply an additional yieldable bias thereto which tends to hold the same closed notwithstanding the influence of a draft through the stack that tends to open the same. However, if the draft through the stack attains such proportions as

30 to be liable to generate in the heater more heat than can be absorbed with safety and efficiency in the system then the check draft damper will open notwithstanding the action of its weight and of its auxiliary biasing means, the auxiliary biasing means yielding

to permit opening of the check draft damper under such circumstances.

Organized with the check draft damper is a positively controlled direct draft damper. This direct draft damper is incorporated in 55 the ash pit structure and is suitably biased to closed position as by a weight. For opening the check draft damper a conventional regulator, such as a diaphragm regulator, is provided, the regulator being connected to 60 the dome of the furnace and acting to swing a weighted lever having an arm connected by a chain to the weighted arm of the direct draft damper. In this way the condition of the heating medium in the boiler or furnace 65 regulates the opening and closing of the direct draft damper and does this positively. This is especially advantageous with banked or slow burning fires where positive opening 70 of the direct draft damper is desirable in order to accelerate combustion.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a view illustrating one embodiment of the invention partly in side elevation and partly in vertical section taken on line 1-1 of Figure 2 and with parts broken away and parts omitted for the sake of illustration;

Figure 2 is a view in front elevation of the check draft damper and its controls;

Figure 3 is a fragmentary view in section taken on line 3-3 of Figure 2; and

Figure 4 is a similar view taken on line 4-4 of Figure 2.

Referring to the drawings, the numeral 1 designates a heating plant which may be of any conventional or known type, such as a hot air furnace, a hot water, a steam or vapor boiler, a gas fired furnace or an oil fired furnace. The present invention is adapted for use on any of the various types of heating plants. The combustion space of the heater connects by a smoke pipe 2 to a stack or chimney 3.

An opening 4 is cut in the stack 3 and receives and supports a reduced extension 5 of a box-like casing 6, the casing 6 being suitably secured in the position shown in Figure 1. 5 Both ends of the casing are open, the inner end having direct and unobstructed communication with the interior of the chimney and the outer end communicating with the atmosphere under the control of a check draft 10 vane or damper 7. When the damper 7 is open air freely flows into the stack 3 to provide a check draft thereinto which, because of its venting action and also because of its cooling action on the gases in the stack, cuts down 15 the draft through the stack and the amount of air pulled through the fire and consequently retards combustion in the heater.

The damper 7 is freely pivoted on the end wall of the casing 6 by means of offset or 20 eccentric pivot pins or trunnions 8 threaded through the end walls of the casing and extending into sockets or bearings 9 provided on the damper. Because the damper 7 is so pivotally mounted, the draft acting on the 25 larger area thereof below the pivots or trunnions 8 tends to swing the lower portion of the damper inwardly and the outer portion thereof inwardly, as shown in Figure 1. In order to restore the static balance of the 30 damper disturbed by the offset or eccentric pivoting thereof, a symmetrically distributed enlargement or weighted portion 10 is provided along the upper edge thereof.

For the purpose of biasing the damper to 35 closed position, in which position its lower edge engages a stop lug 11, an adjustable weight 12 is provided and is fixed to and supported upon the inner end of a screw 13 adjustably fitted in a bearing provided on the 40 damper 7 and disposed with its axis intersecting the axis of swing of the damper and in a plane at right angles to the plane of the damper and passing through its axis. A nut 14 is threaded on the screw 13 and is held 45 against axial movement and releasably secured in any angular adjustment by a flat spring 15 fastened to the damper and bearing on the nut. The end of the spring 15 also constrains the screw 13 to axial movement in 50 that it engages a flat 13' provided on the screw. The weight 12 may be adjusted to maintain the damper 7 closed until the draft through the stack exceeds a predetermined value.

55 In many instances, however, it is desirable to have the combustion in the boiler or furnace accelerated even after the draft in the stack has increased to or beyond the point at which it would be effective to open the check draft damper 7 against the action of its biasing weight 12. Thus, where the boiler or furnace is associated with the heating system there is a considerable lag between the acceleration of the combustion in the heater 60 and the rise in temperature in the heating

medium or the desired rise in the room temperature. Frequently rapid or accelerated combustion must be sustained over a considerable period to bring the temperature of the heating medium or the room temperature 70 up to the desired point.

In order to provide for sustained acceleration of combustion and yet prevent combustion from progressing or continuing beyond the point where the heat generated can be 75 absorbed with safety and efficiency in the system, the check draft damper 7 may be further regulated in its action by means of an auxiliary control. While this auxiliary control may take several forms only one type 80 is illustrated, and, as shown, comprises an electromagnet 20 supported in a casing 21 fixed to one of the end walls of the damper casing 6. The excitation of the windings of the magnet 20 is controlled by an ordinary 85 room thermostat 22', the terminals of the windings 20a of the magnet being connected in circuit with the thermostatic switch of the room thermostat, as illustrated in Figure 3 or in any appropriate manner. An armature 90 22 of laminated iron is secured between carrier plates 23 of insulating material by means of bolts and nuts 24. The plates 23 are pivotally or rockably supported on a supporting pin 25 extending loosely through openings in 95 the plates and secured to the back wall of the casing 21. The armature 22 is curved slightly so that in one position its ends lie in close proximity to the pole pieces 20' of the electromagnet. A yieldable arm 26 which may be 100 of flat resilient metal has one end secured to a screw or bolt 27 extending between and fastened to the plates 21 at one corner of the carrier and has its other end weighted as indicated at 28. The weight 28 and the 105 weight of the arm 26 biases the armature 22 to the position shown in Figure 3 wherein its ends are moved a slight distance away from the pole pieces of the magnet.

110 As shown in the drawing the arm 26 extends through a slot in the casing 21 and projects into adjacent proximity to the damper 7. A pin or projection 29 is secured to the damper 7 along the line of its axis of rotation and has an offset outer end 29' adapted to be engaged by the yieldable arm 26 when the yieldable arm is rotated or shifted up to the position shown in dotted lines in Figure 3. It is obvious that the plates 23 in their 115 connecting parts constitute a shiftable support or shiftable carrier for the biasing arm 26 and that shifting of the support controls the coaction of the biasing arm with the damper. Excitation of the magnet will attract the ends of the armature 22 into close proximity to the pole pieces and in so doing 120 will rock the armature and its carrier and consequently rock the arm 26. When the room thermostat calls for heat its contacts 125 will complete the electrical circuit in which

the windings of the armature are incorporated thereby exciting the magnet and positioning the arm in engagement with the projection 29. When the arm 26 engages the projection 29 it tends to hold the check draft damper 7 closed and any opening of the damper at such times is against not only the action of its biasing weight 12 but also against the yieldable resistance afforded by the arm 26. In the event that the draft so increases as to be liable to accelerate combustion beyond the point where the heat generated can be absorbed with safety and efficiency in the system the increased suction on the damper 7 will cause it to swing inwardly, the arm 26 flexing under the pressure of the projection 29 to permit of the opening of the damper 7. This maintains the amount of air pulled through the fire at the desired value. When the temperature of the room rises to the selected point the room thermostat breaks the circuit in which the electromagnet is incorporated and the arm 26 drops down to the position shown in Figure 1, in which position the draft must overcome merely the force of the biasing weight 12 to effect opening of the check draft damper. Reference is made to my copending application for Heater controls (Case "A") Serial No. 371,074, filed under even date herewith for a full disclosure of the details of construction of this electromagnetically controlled auxiliary biasing means.

A direct draft opening 30 is provided in the ash pit of the furnace and is controlled by a direct draft damper 31 having a weighted arm 32 fixed to its axis of rotation and connected by a chain 33 to a lever 34 fulcrumed as at 35 on a regulator casing 36. Adjustable weights 37 and 38 may be provided on the lever 34. Just beyond this fulcrum the lever 34 is operatively connected as at 39 to the diaphragm (not shown) of the regulator 36. The regulator 36 may be of any conventional construction and as these regulators are widely known and used no detailed disclosure thereof is deemed necessary. Where a banked or slow fire is to be maintained it is advantageous to have a positively and automatically controlled direct draft damper in combination with the balanced and variably biased check draft damper for, with a slow burning fire, the draft through the stack is at times, very slight and it is desirable to accelerate the draft by positively opening the direct draft damper when more heat is desired and combustion is to be increased. When the temperature or pressure of the heating medium rises to the point for which the regulator 36 is set the lever 34 is swung in a counter-clockwise direction as viewed in Figure 1 to permit the damper 30 to close under the influence of its weight 32.

The invention claimed is:

1. A control for heaters comprising a

damper casing having its ends open and having one end communicating with the stack for the heater and the other end communicating with the atmosphere, a balanced damper supported on said casing for free movement under the influence of a draft, an adjustable bias for the damper operating to prevent movement thereof until the draft has reached a predetermined value, a direct draft damper and a diaphragm regulator connected to the direct draft damper and positively controlling the opening and closing thereof in response to conditions in the heater.

2. A control for heaters comprising a check draft damper freely supported so that the draft through the stack tends to open the same, an adjustable overbalance mounted on the damper and tending to close the same while permitting the damper to open when the draft in the stack exceeds a predetermined maximum, room thermostat controlled means for applying an additional yieldable bias to the check draft damper, a direct draft damper, and means responsive to conditions in the heater for positively controlling the opening and closing of the direct draft damper.

3. A control for heaters comprising a check draft damper freely supported so that the draft through the stack tends to open the same, variable biasing means for urging the check draft damper to closed position, room thermostat controlled means for varying the action of the biasing means, a direct draft damper, and means responsive to conditions in the heater for positively controlling the opening and closing of the direct draft damper.

In witness whereof, I hereto affix my signature.
